CLAIM

The ornamental design for an abrasive skin treatment device, as shown and described.

DESCRIPTION

FIG. 1 is a top, front, left perspective view of an abrasive skin treatment device in accordance with the present design; FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines, showing the linear oval detail, the rows of smaller, polygonal details within the oval region, and the residual area, within the oval region but outside of the rows of polygons, represent portions of the abrasive skin treatment device which form no part of the claimed design.
